UNITED STATES PATENT OFFICE.

WILLIAM HAWKS, OF CHICAGO, ILLINOIS.

DESIGN FOR A BURNER-CASING.

SPECIFICATION forming part of Design No. 35,509, dated December 31, 1901.

Application filed September 16, 1901. Serial No. 75,626. Term of patent 3½ years.

To all whom it may concern:

Be it known that I, WILLIAM HAWKS, a citizen of the United States, and a resident of Chicago, in the county of Cook and State of Illinois, have invented and produced a new and original Design for a Burner-Casing, of which the following is a specification.

In the accompanying drawings, Figures 1 and 2 are side views of a burner-casing embodying my invention at ninety degrees from each other, the upper portion of Fig. 2 being in section.

The upper end of a burner-casing of my design consists of an open-ended barrel 1. Surrounding said burner-casing at a distance from the open end of the barrel 1 is a cup 2, and formed in said casing beneath said cup

2 is a transverse hole or opening 3. Extending upwardly from the lower end of the casing is a rib or projection 4, and formed on said casing diametrically opposite the upper end of the rib or projection 4 is a boss 5.

I claim—

The design for a burner-casing, substantially as herein shown and described.

In testimony that I claim the foregoing as my invention I affix my signature, in presence of two subscribing witnesses, this 27th day of August, A. D. 1901.

WILLIAM HAWKS.

Witnesses:

H. H. ROUNTREE,
M. S. SOMERVILLE.
